OSCAR HEYMAN, OF NEW YORK, N. Y.

JOINTED JEWELRY AND PROCESS OF MAKING SAME.

1,173,427.

Specification of Letters Patent. Patented Feb. 29, 1916.

Application filed June 25, 1915. Serial No. 36,194.

To all whom it may concern:

Be it known that I, OSCAR HEYMAN, a citizen of the United States, residing at New York, and whose post-office address is No. 5 71 Nassau street, city, county, and State of New York, have invented certain new and useful Improvements in Jointed Jewelry and Processes of Making Same; and I do hereby declare the following to be a full, 10 clear, and exact description of the invention, such as will enable others skilled in the art to which it appertains to make and use the same.

The invention relates to jointed pieces of 15 jewelry and the like, particularly to a series of jointed pieces suitable for making bracelets, and to an improved method of making such pieces.

The following disclosure of the preferred 20 form or practice of the invention deals with the formation of a section of a bracelet, since that is the purpose to which the invention is primarily directed, but it will be understood that the invention is applicable to 25 the jointing of any piece of jewelry or other article in which the parts are small and delicate and consequently difficult to handle.

It is common practice to make up bracelets by uniting a series of sections to one another by means of hinges. For this purpose 30 the practice is to form in the abutting surfaces of two sections, half cylindrical recesses adapted to receive small sections of tubing which really constitute the knuckle 35 members of a hinge. These sections of tubing are secured to the abutting faces of the sections in such manner that the tube sections will fit into one another in the form of a hinge and then a pintle is run through 40 the tube sections to unite the parts. This involves a series of welding operations corresponding to the number of knuckle members in the hinge; it is a tedious and delicate 45 operation which can be performed only by skilled operators, and it results in a hinge which is weak because the tube sections are 50 separate attached pieces which cannot be reliably secured in place.

The purpose of the present invention is to 55 render this operation less difficult and at the same time to produce an article of manufacture in which the hinges are much more securely fastened to the hinged bar sections or the like. To this end I employ, instead 60 of the tube sections usually used for the

knuckle members, pairs of hinge plates which carry and are preferably made integral with the knuckle members. It is a simple and cheap machine operation to form such hinge plates in one piece and they can 60 be produced at very slight expense. In accordance with my invention, these hinge plates, preferably integral with the knuckle members, are secured to the abutting surfaces of the sections to be hinged together. 65 This is most conveniently and satisfactorily accomplished by uniting the hinge plates to the adjacent surfaces of the sections by a process of welding, and in using the word welding I intend to include processes of 70 soldering. Ordinarily, the welding will be effected by soldering with the same metal that the hinge plates and bar sections are made of, that is, by autogenous soldering; but it may be effected by the mere application of heat or pressure, or by using a different metal as solder. The hinge plates so 75 united with the bar sections are very secure and they are also easily applied as compared with the application of the much smaller 80 and more numerous knuckle members; and bar sections to which these hinges have been applied can be united by bringing them together and placing a pintle through the knuckle members in the usual way. I prefer, however, to form the series or plurality 85 of bar sections hinged together from an integral bar, since this is an operation which can be rapidly carried out and will produce a more satisfactory alignment and connection of the ultimate bar sections. In order 90 that this preferred method may be fully understood, reference is made to the accompanying drawings, in which—

Figure 1 shows in elevation and partly in section the integral bar; Fig. 2 is a view looking at the under side of the bar of Fig. 1; Fig. 3 shows the bar after the hinges have been applied and the bar has been cut into sections; Fig. 4 shows two sections of the completed bar separated at a hinge; Fig. 5 is an end view of one of the sections; and Fig. 6 shows two separated sections in perspective.

In carrying out the invention, I start with 105 an integral bar of any desired shape. In Fig. 1 I have represented a channel bar 1. In this bar, at uniformly spaced intervals corresponding to the desired length of the individual sections of the completed bar, I 110

cut hinge-receiving recesses 2. In these recesses I place pairs of hinge plates 3, 4, carrying coöperating knuckle members 5, 6. These knuckle members are preferably formed integral with the hinge plates. I then unite the plates 3 and 4 with the adjacent surfaces of the recess, and this is preferably accomplished by a process of welding as above described, and as indicated by the 10 cross-section lines in Figs. 1, 2, 3 and 6. A pintle 7 is then run through the knuckle members and the hinge is completed. After this operation has been performed in each of the series of recesses of the bar, the bar is 15 divided into sections by cutting through from the top as indicated at 8 in Fig. 3, the result being a completed chain of bar sections hinged together. It will be understood that the walls of the recesses 2 will be 20 slightly flared so that when the hinge is in place it will be slightly opened as indicated in the drawings, and consequently when the sections are separated at 8, the completed chain of sections may be flexed within desired limits as indicated at Fig. 4.

What I claim is:

1. The method of producing from an integral bar a plurality of bar sections hinged together for jewelry and the like, which consists in forming a series of spaced hinge-receiving recesses in and extending partially through the bar, securing in the recesses pairs of hinge plates carrying coöperating knuckle members, and cutting through the 30

bar at the hinges to divide it into sections; 35 substantially as described.

2. The method of producing from an integral bar a plurality of bar sections hinged together for jewelry and the like, which consists in forming a series of spaced hinge-receiving recesses in and extending partially 40 through the bar, placing in the recesses pairs of hinge plates carrying coöperating knuckle members, welding the plates of each pair to the adjacent surfaces of the recess, and cutting through the bar at the hinges to divide it into sections; substantially as described. 45

3. An article for the manufacture of jewelry or the like, comprising hinged bar sections arranged end to end, each member being recessed at opposite ends so that an overhang is provided atop each of said recesses, and a knuckle-carrying hinge plate secured in each of said recesses so that the outer surface of each hinge plate forms a 50 55 flush continuation of the end face of the overhang thereabove.

4. An article for use in the manufacture of jewelry and the like, comprising an integral bar containing a series of hinge-receiving recesses, pairs of hinge plates in said recesses and united with the adjacent walls thereof, and coöperating knuckle members carried by said hinge plates, substantially as described. 60

In testimony whereof I affix my signature.

OSCAR HEYMAN.
